C. E. HAVILAND.
ORNAMENTATION OF DISHES.

No. 19,849.

Patented May 27, 1890.

UNITED STATES PATENT OFFICE.

CHARLES ED. HAVILAND, OF LIMOGES, FRANCE.

DESIGN FOR THE ORNAMENTATION OF DISHES.

SPECIFICATION forming part of Design No. 19,849, dated May 27, 1890.

Application filed November 20, 1886. Serial No. 219,530. Term of patent 14 years.

To all whom it may concern:

Be it known that I, CHARLES EDWARD HAVILAND, a citizen of the United States, residing at the city of Limoges, in the Republic of France, have invented and produced a new and original Design for the Ornamentation of Dishes, which is described and fully represented in the following specification and accompanying illustration, forming a part of the same.

The accompanying figure illustrates, as one of the many dishes to which this design is applicable, a perspective view of a plate embodying said design.

The characteristic feature of this design is the ornamental pattern composed of sprays

of roses, the leaves and petals of which are delineated substantially as is shown in the accompanying illustration. As an additional feature, sprays bearing stellated flowers are shown as associated with the sprays of roses.

What I claim is—

The design for a dish, consisting of the surface ornamentation, substantially as shown and described.

In testimony whereof I have hereunto set my hand in the presence of two subscribing witnesses.

CH. ED. HAVILAND.

Witnesses:

F. CATE,

A. SERIEQUE.
